APPARATUS FOR CALCULATING THE SPACING OF TYPE FOR PRINTED MATTER

James D. Bolongaro, Charlottesville, Va.

Application November 27, 1934, Serial No. 754,971

9 Claims. (Cl. 235—61)

This invention relates to the art of printing and more particularly to a device that may be used in combination with typewriting machines to determine the number of printed lines of a predetermined type and length that the typewritten matter will occupy.

In the printing art it is necessary to predetermine the spacing of the type that will be required to print the subject matter of a typewritten manuscript or other copy, in order properly to make up the printed matter and so that the latter will present a uniform and artistic appearance. This is particularly true in the printing of books, magazines and periodicals which comprise a plurality of successive pages over which the printed matter is to be distributed and which include other matter, such as illustrations, inserts, and the like, which encroach upon the "sight" or printing field of the page. In such publications, the pages are of the same size and the printing fields are uniformly dimensioned to receive a predetermined number of printed lines of given lengths.

It is the object of this invention to provide a novel and simple device to be used in combination with a typewriting machine that will additively give the number of printed lines of a predetermined type and length that the typewritten matter will occupy as the matter is being typed, in order that an editor may be enabled to lay out accurately before printing the amount of printed space that the typewritten manuscript or copy will occupy.

According to my invention there is provided means in cooperative relation with the carriage or escapement wheel of a typewriter which moves a unit distance corresponding to the unit distance through which the carriage or escapement wheel moves after a type key or space bar has been depressed. Operatively connected to and controlled by such means is a gear member which rotates a corresponding unit distance proportional to the space occupied by a printed letter of predetermined size, said gear being operatively connected to means which operate a counting mechanism when the gear has moved a number of unit distances equivalent to the number of letter spaces contained in a printed line of a predetermined length.

In the accompanying drawings I have illustrated several preferred embodiments of such apparatus but would have it understood that my invention is not limited to these particular forms.

Referring to the accompanying drawings:

Fig. 1 is a rear elevation of a Remington type-

writing machine embodying my invention; Fig. 2 is a section taken on the line 2—2 of Fig. 1; Fig. 3 is a partial front elevation and a partial vertical section of my device, through the line 3—3 of Fig. 2; Fig. 4 is a plan view of that portion of my device which is shown in Fig. 3; Fig. 5 is a partial front elevation of my device looking along the line 5—5 in Fig. 2; Fig. 6 is an enlarged detail of a portion of my device looking along the line 6—6 of Fig. 2; Fig. 7 is a plan view of an Underwood typewriting machine embodying my invention, the carriage being removed; Fig. 8 is a rear elevation of Fig. 7 showing the carriage in position; Fig. 9 is a partial vertical section taken on line 9—9 of Fig. 8; Fig. 10 is a partial front elevation of my device looking along the line 10—10 of Fig. 7; Fig. 11 is a partial front elevation of my device looking along the line 11—11 of Fig. 7; and Fig. 12 is a section taken on line 12—12 of Fig. 10.

Referring to Figs. 1 to 6 inclusive, the numeral 1 indicates the customary base of a Remington typewriting machine having corner pillars 2 affixed thereto upon which is mounted a top plate 17. Attached to the top plate 17 of the machine are the usual guide rails 6 which have their opposite faces grooved for the reception of antifriction rollers 5. The rollers are likewise received in the oppositely grooved rails 4 attached to the end bars 3 of the carriage which are provided with bearings to receive a platen shaft 7 on which 30 a rotative cylindrical platen 8 is mounted. The carriage in this machine comprising the end bars 3 and the rails 4 is thus mounted for sidewise movement over the top plate 17 of the machine.

Attached to the top plate 17 is the usual bearing 22, in which is journaled shaft 21 having mounted thereon the escapement wheels 26, 27, the space back ratchet 25, and the rack gear 20, the latter meshing with the space rack 11 which is attached by means of screws 12 to a frame member 10 pivotally mounted at 9 on the carriage. A pivoted lever not shown is adapted to raise the space rack 11 about its pivot 9, disengaging it from the rack gear 20, in order that the carriage may be moved freely from side to side without affecting the other elements in the machine.

As stated above, the mechanism thus far described constitutes part of the usual equipment 50 of the Remington typewriting machine and further detailed description of the known parts of such machine is deemed unnecessary and only those parts have been shown which cooperate with my device. The usual operation of the machine 55

is in no wise affected by the incorporation of my device therein as will be hereinafter explained.

Extending rearwardly from and supported by the space rack 11 are rods 13 which support a member 15 in parallel relation to the space rack 11. Depending from and fixedly attached to the member 15 by rivets 18 (Fig. 1) are bars 14, to the lower ends of which is fixedly attached by rivets 18 a rack 16 whose teeth are adapted to engage the teeth of a gear 36 mounted on shaft 34. By this arrangement the rack 16 is rigidly supported by the space rack 11, in parallel relation thereto, so that they move simultaneously through equal distances when the carriage is caused to move horizontally from side to side.

In a Remington machine of the type shown in Figs. 1 and 2, the carriage, upon which is rigidly mounted the space rack 11, has a tendency to move in one direction under the tension of a spring member (not shown) mounted on the frame of the machine, to rotate gear 20 and the escapement wheels 26, 27 but is held in place by an escapement pawl (not shown) which alternately engages teeth in the escapement wheels 26, 27. When a type key is released after having typed the desired letter on a sheet of paper mounted on the platen, the escapement pawl, which at this stage holds the carriage in place through engagement with a tooth on the escapement wheel 26, is caused to move about its pivot into the path of rotation of the escapement wheel 27 whose teeth are staggered with respect to the teeth on the escapement wheel 26 as shown in Fig. 1. The carriage is then free to move a portion of a letter space, whereupon it will be stopped by a tooth on the escapement wheel 27 engaging the escapement pawl. When the next type key is depressed the escapement pawl is moved back into the path of rotation of escapement wheel 26 allowing the carriage to move the remainder of the letter space just before the type bar strikes the paper on the platen. Thus in this machine, the carriage is allowed to move a portion of one letter space in the direction of pull of the spring 45 as one type key is returning to its normal position and the remainder of the letter space as another type key is raised to strike. The teeth of the space rack 11 and the gear 20 are of such a size that each one is equal in width to one letter space. Thus as the platen moves through a distance equal to the width of one letter space the rack 11 and the gear 20 move through a space occupied by one tooth. As the rack 11 moves through a unit distance equal to the space occupied by a typewritten letter, the rack 16 rigidly attached thereto also moves through the same unit distance to rotate the gear 36 through a corresponding unit distance. Gear 36 is similar to gear 20 so that as the carriage moves through a letter space the two gears simultaneously move an equal unit distance with their respective shafts.

The shaft 34 is journaled in a bearing 31 mounted on a supporting plate 32 and has mounted on its other end a disc 40. Pivoted attached to the disc 40 at 43 is a spring-tensioned pawl 44 adapted to engage the teeth of a ratchet 41, which is mounted on the end of shaft 48, for rotation in the same direction that the carriage moves during the operation of the machine, but when the carriage is moved in the opposite direction the pawl is adapted to ride over the teeth of ratchet 41 without actuating the latter. Mounted adjacent to or integral with the ratchet 41 is a ratchet 42 of smaller diameter. A spring-

tensioned pawl 45 is pivotally mounted at 46 upon the supporting plate 31 and is adapted to ride over the teeth of ratchet 42 while the latter is rotating in the same direction that the carriage moves during the operation of the machine, but when the carriage is moving in the opposite direction, the pawl 45 is adapted to engage the teeth in ratchet 42 to prevent rotation of shaft 48.

Mounted on shaft 48 exteriorly of the supporting plate 31 is a disc 47 and gears 50 and 51. Gears 50 and 51 are designed to have the same number of teeth that gears 20 and 36 have. Attached to the supporting plate 31 is a bracket 53 supporting a leaf spring 52 that is adapted to ride on the teeth of gear 51 to prevent over-running of the shaft 48 so that the gear will revolve through a distance of only one tooth as the space rack 11 is moved one letter space by the carriage. Thus, by this arrangement, when the platen 8 is moved in the operating direction through a distance equal to the space occupied by a letter of the particular type used in the machine, gear 50 through the racks 11 and 16, and gear 36, shaft 34, disc 40, pawl and ratchet 44, 41 and shaft 48, is rotated through a unit distance corresponding to the space occupied by a typewritten letter. In the present instance gears 20, 36, 50 and 51 have twelve teeth so that when they have made a complete revolution they will have moved a distance corresponding to the space occupied by twelve letters of typewritten type on a sheet of paper.

Rotatably mounted on the disc 47 at 55 so as to be in mesh with gear 50 is an idler gear 54 connecting gear 50 with a gear 56 mounted on a shaft 57 journaled in the supporting plates 31, 32. Gear 56 is so designed that one complete revolution thereof corresponds to the number of letter spaces contained in a printed line of a predetermined length. In order to arrive at the dimensions of the gear 56, it is first necessary to make an actual count of the letters, marks and spaces between words (herein called letter spaces) on printed full lines of the medium in which the manuscript is to be printed and to make that count over an extended number of such printed pages, say ten to twenty. From a large number of counted lines, the average number of letter spaces in the lines of such printed pages is obtained. This theoretical predetermined printed line gives me a yardstick which, I have found, enables me to determine with almost perfect precision or accuracy the space which will be occupied in the printed medium by a typewritten manuscript. Having determined the average number of letter spaces contained in full lines of the particular magazine or medium in which the manuscript is to be incorporated, the gear is then designed so that one complete revolution thereof corresponds to the number of letter spaces contained in such predetermined printed line. The same principles apply when the typewritten matter is to be incorporated in a medium having printed type of a different kind or having a single page of different dimensions, the construction of the gear 56 depending upon the new predetermined printed line that is obtained. Attached to the shaft 57 is a cam 63, adapted to engage and gradually depress a roller 80 extending from the adjacent end of a lever 81 (Figs. 3 and 4) pivoted at 82 on the supporting plate 32, as the gear 56 is rotated during the operative movement of the platen. As the one end of the lever 81 is being depressed by the cam 63, the other end rises to 75

lift a spring tensioned arm 85 on a counter mechanism 86. Cam 63 is so designed that when the gear 56 has made one complete revolution, the lever 81 has rotated the arm 85 against the tension of its spring to such a point that the counter mechanism 86 is caused to operate. The roller 80 supporting end of the lever 81 then returns to its starting position under the influence of the spring tensioned arm 85, as the cam reaches 10 the position shown in Fig. 3. In this way there is registered in the counting mechanism the number of printed lines of a predetermined type and length that the matter typed by the machine would occupy.

15 Gear 56 is interchangeable with other gears, each one of which is so designed that one complete revolution corresponds to a printed line of a predetermined length having letter spaces of a predetermined type. When it is desired to
20 change gear 56, the bolt 46 which extends through a guide or slot 49 in the disc 47 and engages the supporting plate 31, is loosened and the disc is moved counter-clockwise (see Fig. 1) about the shaft 48 so that the gear 54 is disengaged from
25 the gear 56. Gear 56 may then be removed by removing the nut 60 and a new gear 56 put in its place. When the new gear has been positioned on the shaft 57, the disc 47 is moved clockwise until gears 56 and 54 are in mesh, the disc
30 being then locked in position by tightening the bolt and nut. 68

Gear 54 may also be replaced with another gear if the one then on the machine does not properly connect gear 50 with the new gear 56. In replacing gear 54, the bolt and nut 46 are first removed to release the disc 47. The gears 50 and 51 and the disc 47 are then removed from the shaft 48. Disc 47 is then replaced by another disc carrying a new gear 54 so positioned thereon that it will mesh with gear 50 when the latter is replaced in the shaft 48. The bolt and nut 46 are then replaced to hold the disc 47 in position against the plate 31 wherein the new gear 54 meshes with gears 50 and 56. Thus by changing the arrangement of the gears the device may be used to count letter spaces of typewritten matter of a predetermined type in terms of printed lines of various types and lengths.

Operatively attached to the shaft 57 by the coupling member 64 is a shaft 59 slidably supported at its other end by a bearing 65 in the end of a bracket 72. A disc 66 is mounted on the end of shaft 59, the disc having suitable legends thereon for different positions of the cam 63, for example the legends $\frac{1}{4}$, $\frac{1}{2}$, $\frac{3}{4}$ will indicate that the cam has rotated through 90° , 180° , or 270° with its shaft 57 when in the position occupied by the arrow in Fig. 5, the latter indicating that the cam is at its starting position as shown in Fig. 3. Attached to the outer end of shaft 59 is a knurled hand nut 67 by which the operator may rotate shaft 59 to bring the cam 63 and gear 56 to their starting positions when the device is about to be used or when it is desired that a short typewritten line shall occupy a single printed line. In the latter case the counter 86 is caused to operate independently of the typewriting machine.

Shafts 59 and 57 may be moved horizontally to the rear by pressing the knurled nut 61 against the pressure of spring 61 seated between the supporting plate 31 and a collar 62 affixed to the shaft 57 by a set screw, to move gear 56 out of engagement with gear 54 so that the typewriting machine may be operated without operating the counting mechanism. Pivoted at 70 on the

bracket 72 is a lever 69 whose free end 71 normally rests on a flange of a hub 68 mounted on the shaft 69 as shown in Fig. 2. When the knurled nut 67 is pushed to the rear, the hub 68 moves therewith allowing the free end of lever 69 to drop between the disc 66 and the hub 68. A notch 73 in the free end of lever 69 is adapted to engage the shaft 59. In this position of the lever 69, the hub 68 serves as a stop to prevent the shafts 57 and 59 from returning to their normal positions, under pressure of spring 61 whenever gear 56 meshes with gear 54, until lever 69 is tilted about its support 70 to disengage the notched end 71 from the shaft 59 and clear the hub 68.

The supporting plates 31, 32 are suitably mounted on a bracket 30 attached to the base 1 of the machine and are maintained in spaced relation by the sleeves 33. 15

In Figs. 7 to 12 inclusive, there is shown another embodiment of my invention in combination with an Underwood typewriting machine having the usual carriage slidably mounted on the longitudinal rods 80 and provided with bearings to receive a platen shaft on which a rotatable cylindrical platen 86 is mounted. Attached to ends 87 of the usual pivoted supporting arms is the space rack 88 which is adapted to ride on the gear 89 rotatably mounted on a shaft 90 journaled in the bearing 91 (Fig. 7). A toothed escapement wheel 92 carrying a spring-tensioned pawl 93 is mounted on the shaft 90, the pawl being adapted to engage the rotatably mounted gear 89 when the carriage is moving in one direction under the pull of member 94 attached at 95 to the carriage and adapted to be wound about a spring tensioned reel 96 rotatably supported on a bracket 97 mounted on the frame 98. When the carriage is moving in the opposite direction against the pull of member 94, the pawl 93 is adapted to ride over the teeth of the gear 89 without imparting motion to the shaft 90 and the escapement wheel 92 which is prevented from rotating in that direction by an escapement pawl (not shown).

The mechanism thus far described constitutes part of the usual equipment of the Underwood typewriting machine and further detailed description of the machine is deemed unnecessary and only such parts have been shown as cooperate with the parts of my improved attachment.

Attached to the end of shaft 90 is a hub 100 having a disc 108 fixedly attached at its outer end. A spring tensioned pawl 109 is pivotally mounted at 107 on the disc 108 and adapted to engage the teeth of a ratchet 110 mounted on the shaft 101 to move the ratchet through an angular distance equal to that moved through by the gear 89 and the escapement wheel 92 when the carriage, in the operation of the machine, moves through a unit distance equal to that occupied by a typewritten letter. The ratchet 110 has the same number of teeth as the gear 89. The pawl 109 is so positioned and the ratchet 110 is so designed that the latter can be moved in only one direction by the pawl. By this arrangement the ratchet 110 may be rotated by the disc 143 without rotating shaft 90 as will be herein-after explained. The shaft 101 is journalled in the supporting plates 102, 103 which are held in spaced relation by sleeves 104 and are supported on a bracket 106 mounted on the frame of the machine by screws 105 which threadedly engage said bracket. A spur gear 111 having the

same number of teeth as the ratchets 110 and 89 is also mounted on the shaft 101.

Thus the carriage, to which is rigidly attached the space rack 88, has a tendency to move in one direction under the tension of member 94 to rotate the gear 89 and through the pawl 93 rotate the escapement wheel 92, shaft 90, hub 100, disc 108, and through pawl 109 rotate ratchet 110, shaft 101, and gear 111. It is held in place, however, by an escapement pawl (not shown) which prevents rotation of the escapement wheel in either direction but is adapted to move out of engagement therewith when a depressed type key is released, to allow the escapement wheel to rotate through the space occupied by one tooth. The carriage is then free to move through a distance occupied by one letter space and carries the space rack 88 with it. The rack 88, the gear 89, escapement wheel 92 and the ratchet 110 and gear 111 which in this case have the same number of teeth as gear 89, and escapement wheel 92, all move through the space occupied by one tooth when the carriage moves through a distance equal to the space occupied by a typewritten letter. In other words, as the carriage moves through a unit distance equal to a letter space these elements move through corresponding unit distances.

Meshed with gear 111 is a spur gear 112 (Fig. 9) mounted on a shaft 113 journaled on the supporting plates 102, 103. Also mounted on shaft 113, intermediate the supporting plates 102, 103, is a miter gear 114 in mesh with a miter gear 115 mounted on the end of a shaft 116 rotatably supported in the bearings 127, 128 (Fig. 7) mounted between the supporting plates 102, 103. A miter gear 117 is mounted on the other end of shaft 116 in mesh with a miter gear 118 mounted on the shaft 119 rotatably supported by the plates 102, 103. Mounted on a shaft 119 exteriorly of the supporting plate 103 is a spur gear 120. Gear 112 is by this arrangement operatively connected to gear 120. The spur gears 112, 120 and miter gears 114, 115, 117 and 118 have the same number of teeth so that movement by any one will rotate the others a similar amount about their respective shafts. In the present instance they have more teeth than gear 111 so that they move through angular unit distances smaller than that of gear 111. By this construction gear 120 moves through a unit distance proportional to the unit distance travelled by the carriage in moving through the space occupied by one letter type.

Rotatably mounted on a stud shaft 122 attached to a disc 123, is a spur gear 121 connecting gear 120 with a spur gear 130. The disc 123 which supports the gear 121, is movably mounted on the shaft 119 but is ordinarily held in a predetermined position thereon by a screw 124 which extends through a slot 125 in the disc 123 and is in threaded engagement with the supporting plate 103. A washer 126 is provided between the head of the screw 124 and the disc 123 to provide a larger surface contact between these parts. Gear 130 is mounted on a shaft 131 rotatably and slidably supported by the supporting plates 102, 103 and by a bearing 132 in the end of a bracket 133 mounted by screws 134 on the frame of the machine. Gear 130 is so designed that one complete revolution corresponds to the number of letter spaces contained in a predetermined printed line. Thus, for example, if gear 120, which moves a unit distance corresponding to the distance travelled by the carriage in moving a letter space, is caused to move twenty unit distances, gear 130 will move

twenty unit distances corresponding to the space occupied by twenty letters of a predetermined print. If gear 130 is designed for a printed line having twenty letter spaces of the predetermined print, it will make one complete revolution while gear 120 is moving through twenty unit distances. The manner in which the dimensions of the gear 130 are determined in order that such gear may be used for counting lines for a particular printed medium, is the same as that described with respect to gear 56.

On the shaft 131 intermediate the supporting plate 102 and a lever 135 rotatably mounted on a screw member 105, is fixed a cam 136 similar to cam 63 on the Remington machine. Attached to the lever 135, adjacent its free end, is an arm 137 adapted to ride on the cam 136. Rotatably supported on a screw member 138 which is in threaded engagement with the free end of lever 135 is a rod 139 adapted to slidably engage at its other end an arm 140 on a counter mechanism 141 supported by the plates 102, 103. An abutment 142 is provided on the rod 139 upon which the free end of arm 140 rests, the rod thus oscillating the arm 140 as it is lifted with the end of lever 135 by the cam 136. Thus by this arrangement when the gear 130 is caused to rotate, cam 136 will gradually raise the lever 135 about its pivot, through the medium of arm 137, causing the rod 139 to rotate the lever 140. Cam 136 is so designed that when the gear 130 has made one complete revolution, the lever 135 and rod 139 have rotated the arm 140 to such a point that the counter mechanism is caused to operate. In this way there is registered in the counting mechanism the number of printed lines of a predetermined type and length that the matter being typewritten would occupy.

A disc 143 is fixed to the forward end of shaft 131, the disc having suitable legends thereon in a manner similar to disc 66 of the Remington machine above described to indicate the angular position of cam 136. The disc 143 may also be rotated by hand to bring the cam 136 to its starting position or to rotate the cam to register a printed line even though the typewritten line has ended as in the case where a paragraph has ended or a short typewritten line is to occupy a single printed line as in the case of dialogue.

In a manner similar to shaft 59 of the Remington machine the shaft 131 may be shifted axially to the rear by pushing the end 144 of shaft 131 inwardly against the pressure of spring 146 (Fig. 12) to disengage gear 130 from gear 121, so that the typewriting machine may be operated without operating the counting mechanism. There is also provided a pawl or lever 145 pivoted on the bracket 133 which ordinarily rides on the flange of a hub 147 attached to the shaft 131 but which is adapted to drop in front of said hub when the shaft 131 is shifted to the rear to serve as a stop to prevent the shaft 131 from moving forward until the lever 145 is lifted clear of its flange.

In a manner similar to that described with regard to the changing of gears 54 and 56 on the Remington machine the respective gears 121 and 130 may be changed so that the device will count the matter typed by the machine in terms of printed lines, of other types and lengths.

Thus, according to the structures described, when the escapement pawl in either the Remington or Underwood typewriting machines allows the carriage to move through a distance equal to the space occupied by a typewritten letter, after

a type key or the space bar has been operated, there is caused to move through a corresponding unit distance a gear (gear 51 in the Remington machine and gear 120 in the Underwood machine) which is operatively connected either to the carriage, as in the Remington machine, or to the escapement wheel, as in the case of the Underwood machine. This gear, which is operatively connected to a second gear (gear 56 in the Remington machine and gear 130 in the Underwood machine) causes the latter to move a corresponding unit distance proportional to the space occupied by a letter of printed type. The second gear is so designed that it makes a complete revolution when it has moved through a number of unit distances corresponding to the number of spaces of type contained in a predetermined printed line. In both machines there is mounted on the same shaft with the second gear, a cam which is so designed that when the second gear makes a complete revolution it causes a counting mechanism operatively connected thereto, to operate. Thus there is registered in the counting device, as the matter to be printed is being typed, the number of lines of print of a predetermined length and type that the type-written matter will occupy.

From the foregoing it will be seen that my invention makes it possible for authors who type-write their own manuscripts, and for printing or publishing houses where matter to be printed is first put in typewritten form, to know as soon as the manuscript is typewritten how many printed lines of a given length and type, the manuscript will require. Placing this information in the hands of an editor will save him much time and trouble in laying out the magazine or periodical as he can plan it just as he would like to have it without being subjected to the necessity of rearrangement and modification when the copy is returned from the printer.

While I have illustrated and described two embodiments of my invention in combination with a Remington and an Underwood typewriting machine, it will be understood that it can be used in combination with any typewriting machine and that various changes in the form, construction and arrangement of the several parts may be resorted to without departing from the spirit and scope of my invention; hence I do not wish to limit myself strictly to the structure herein set forth.

What is claimed is:

1. In a machine for printing on a surface characters of a predetermined type in lines of a predetermined length, the combination with mechanism for advancing said surface through character space distances during the printing operation of the machine, of means controlled by such mechanism and arranged to move through unit distances as said surface is advanced through the character space distances in the printing operation of the machine, translating mechanism connected to said first named means and operable to translate the unit movements of said first named means during the advancing movements of said mechanism into the number of lines which the matter being printed will occupy in a different medium having predetermined lines of a different type and length than the lines of characters being printed, means operable to modify the action of said translating mechanism to include in such line count the spacings which will appear in the different medium after paragraph endings of such matter, means intermediate said first men-
- tioned mechanism and said translating mechanism for enabling the latter to be actuated by said modifying means while said surface is at rest, and a counting mechanism operatively connected to said translating mechanism and said modifying means and arranged to register the number of lines of the different type.
2. In a machine for printing on a surface characters of a predetermined type in lines of a predetermined length, the combination with mechanism for moving said surface through character space distances during the printing operation, of cooperating instrumentalities operatively connected to such mechanism and including means adapted to translate the unit movements of said surface as it is advanced during the printing operation into the number of lines which the matter being printed will occupy in a different medium having predetermined lines of a different type and length than the lines of characters being printed, means operable to modify the action of said translating means to include in such line count the spacings which will appear in the different medium after paragraph endings of such matter, means intermediate said mechanism and said translating means for enabling the latter to be actuated by said modifying means while said surface is at rest and a counter connected to said translating means and said modifying means and arranged to register the total number of lines of the different type.
3. The combination with a typewriting machine, of mechanism for calculating the number of lines of a predetermined length and of a second size of type that the typewritten matter will occupy in a different medium comprising, cooperating instrumentalities operatively connected to the typewriter mechanism and including means adapted to translate the number of letter spaces produced by depressing the type keys and space bar in the operation of the typewriting machine into the number of predetermined lines of said second size of type that the matter being typed will occupy in the different medium and including mechanism able to modify the action of said translating means to include in said line count the spacings which will appear in the different medium after paragraph endings of such matter and a counter arranged to register the number of lines of said second type as modified by said mechanism.
4. The combination with a typewriting machine, of mechanism for calculating the number of lines of a predetermined length and of a second size of type that the typewritten matter will occupy in a different medium comprising, cooperating instrumentalities operatively connected to the typewriter mechanism and including means adapted to translate the number of letter spaces produced by depressing the type keys and space bar in the operation of the typewriter into the number of predetermined lines of said second size of type that the matter being typed will occupy in the different medium and including co-acting mechanism operable to modify the action of said translating means to include in said line count spacings other than those spaces which will be occupied by the printed characters and which will appear in the printed field of the different medium, means intermediate the typewriter mechanism and said translating means for enabling the latter to be actuated by said coacting mechanism while the type keys and space bar of the typewriter are at rest, a counter connected to said translating means for regis-

- tering the number of lines of said second type as modified by said coacting mechanism, and means included in said coacting mechanism for interrupting the coactive relation of said mechanism 5 without affecting the operation of the typewriter.
5. The combination with a typewriting machine, of mechanism for calculating the number of lines of a predetermined length and of a second size of type that the typewritten matter will 10 occupy in a different medium comprising, a gear operatively connected with the typewriter for moving through unit distances as the platen advances through character space distances during the printing operation, a second gear connected to said first-named gear and adapted to move through unit distances proportional to the spaces occupied by the characters of said second type as the platen is advancing, a counter, means intermediate said second-named gear and said 15 counter for intermittently operating the latter every time said second-named gear has moved through a number of unit distances equivalent to the number of letter spaces in a predetermined line of said second type and co-acting mechanism connected with said intermediate means and operable to modify the action of such means to include in said line count the spacings which will appear in the different medium after paragraph endings of such matter.
- 20 6. The combination with a typewriting machine, of mechanism for calculating the number of lines of a predetermined length and of a second size of type that the typewritten matter will occupy in a different medium comprising, a gear 25 operatively connected with the typewriter for moving through unit distances as the platen advances through character space distances during the printing operation, a second gear connected to said first-named gear so as to move relative to the latter during the advancing movement of the platen and being so designed that one complete revolution thereof corresponds to the total number of spaces in a predetermined line of said second type, a counter, means intermediate said second-named gear and said counter for intermittently operating the latter every time said second-named gear makes a complete revolution and co-acting mechanism connected with said second-named gear and operable to modify the action of such gear to include in said line count 30 the spacings which will appear in the different medium after paragraph endings of such matter.
- 40 7. The combination with a typewriting machine, of mechanism for calculating the number of lines of a predetermined length and of a second size of type that the typewritten matter will occupy in a different medium comprising, a gear operatively connected with the typewriter for moving through unit distances as the platen advances through character space distances during the printing operation, a second gear connected to said first-named gear and adapted to move 45 through unit distances proportional to the spaces occupied by the characters of said second type as the platen is advancing, a shaft supporting said second-named gear and a cam which is fixedly secured thereto, a counter, means intermediate said counter and said cam and cooperating with the latter to cause said counter to register every 5 time said second-named gear has moved through a number of unit distances equivalent to the number of letter spaces in a predetermined line of said second type and co-acting mechanism connected with said second-named gear and operable to modify said line count to include the spacings which will appear in the different medium after paragraph endings of such matter.
- 50 8. The combination with a typewriting machine, of mechanism for calculating the number of lines of a predetermined length and of a second size of type that the typewritten matter will occupy in a different medium comprising, cooperating instrumentalities operatively connected to the typewriter mechanism and adapted to translate the number of letter spaces produced by depressing the type keys and space bar in the operation of the typewriter into the number of predetermined lines of said second type that the matter being typed will occupy in the different medium, said cooperating instrumentalities including a counter arranged to register the number of lines of said second type and means connected with said counter and operable to actuate the latter independently to count letter spaces in 20 terms of lines of said second type and co-acting with said instrumentalities to modify said line count to include the spacings which will appear in the different medium after paragraph endings of such matter.
- 55 9. In a machine for printing on a surface characters of a predetermined type in lines of a predetermined length, the combination with mechanism for moving said surface through character space distances during the printing operation, means controlled by such mechanism and arranged to move through unit distances as said surface is advanced through the character space distances, cooperating instrumentalities operatively connected to said first-named means and operable to translate the unit movements of said first-named means into the number of lines which the matter being printed will occupy in a different medium having predetermined lines of a different type and length than the lines of characters being printed, said instrumentalities including a counting device arranged to register the number of lines of the different type, and indicating means separate from said counting device and connected to said instrumentalities, said indicating means being operable by said instrumentalities to visually indicate to the operator the condition of a particular line count and being so arranged with respect to said instrumentalities that they may be independently operated to modify the operation of said counting device without affecting the operation of the machine.

JAMES D. BOLONGARO.
